US00D934202S

(12) **United States Design Patent** (10) **Patent No.:** **US D934,202 S**
Liu (45) **Date of Patent:** **** Oct. 26, 2021**

(54) **EARPHONE**

(71) Applicant: **Chunhong Liu**, Nanchong (CN)

(72) Inventor: **Chunhong Liu**, Nanchong (CN)

(**) Term: **15 Years**

(21) Appl. No.: **29/738,201**

(22) Filed: **Jun. 16, 2020**

(30) **Foreign Application Priority Data**

Dec. 19, 2019 (CN) 201930712295.9

(51) **LOC (13) Cl.** **14-01**

(52) **U.S. Cl.**

USPC **D14/223**

(58) **Field of Classification Search**

USPC ... D14/205, 207, 217, 221, 223, 224, 224.1, D14/225; D24/173, 174
CPC H04R 1/10; H04R 1/1016; H04R 1/1066; H04R 1/105; H04R 1/1033; H04R 1/08; H04R 5/033; H04R 5/0335; H04R 25/00

See application file for complete search history.
